UNITED STATES PATENT OFFICE.

ELLSWORTH A. HAWTHORNE, OF BRIDGEPORT, CONNECTICUT.

LIGHTING APPARATUS.

1,196,950.

Specification of Letters Patent. Patented Sept. 5, 1916.

Application filed March 24, 1913. Serial No. 756,493.

To all whom it may concern:

Be it known that I, ELLSWORTH A. HAWTHORNE, a citizen of the United States, and a resident of Bridgeport, county of Fairfield, State of Connecticut, (whose post-office address is 35 Spruce street, Bridgeport, Connecticut,) have invented an Improvement in Lighting Apparatus, of which the following description, in connection with the accompanying drawings, is a specification, like characters on the drawings representing like parts.

This invention relates to lighting apparatus and more especially, though not exclusively, to tail lamps for motor vehicles and more particularly motor cycles.

My invention will be best understood by reference to the following specification when taken in connection with the accompanying drawings of one illustrative embodiment thereof, while its scope will be more particularly pointed out in the appended claims.

In the drawings: Figure 1 is a vertical sectional view partly in elevation of one form of lighting apparatus embodying my invention, the electric generator and wiring of the generator circuit being shown diagrammatically; Fig. 2 is a sectional view on line 2—2 of Fig. 1, looking in the direction of the arrows on said line; and Fig. 3 is a plan sectional view on line 3—3 of Fig. 1.

Referring to the drawings and to the embodiment of my invention which I have selected for illustrative purposes, I have there shown a tail-lamp which is arranged to show a red light at the rear as well as to illuminate a number plate. The lamp chosen for purposes of exemplification comprises a lamp-casing 5 provided at its rear with a light-transmitting element 6 herein in the form of a so-called red "jewel," while the bottom of the casing is provided with a light-transmitting element 7 herein in the form of a sheet of clear transparent glass or other transparent substance. These light-transmitting elements may be fitted into suitable apertures in the lamp-casing in any appropriate manner. Preferably the element 6 is mounted in the lamp-casing in such a manner as to be conveniently removable to render the interior of the lamp-casing accessible.

Within the lamp-casing are two suitable lamps 8 and 9 preferably electric incandescent bulbs having different candle-powers. The lamp 8 having the greater candle-power is connected in circuit with a suitable elec-

tric generator 10 of the character usually employed on motor vehicles and driven by the engine. In the use of motorcycles it is desirable and in fact quite customary to stop the engine when the cycle is at rest. Under these circumstances, the engine-driven generator would cease to supply the necessary current to the lamp. As a means for furnishing the required light in order to comply with the law, I provide the low candle-power lamp 9 in circuit with a suitable battery 11, preferably a dry battery. The latter is herein mounted in a battery-casing 12 preferably secured to the lamp-casing 5. A suitable bracket 13 may serve to support both casings.

In the present instance, the lamp 9 extends through the wall of the lamp-casing 5, through the bracket 13, and through the wall of the battery-casing 12. One terminal 14 of the lamp 9 is electrically connected through the metallic casing 12 to a terminal 15 of the battery while the other terminal 16 of the lamp may be connected by a conductor 17 and switch 18 to another battery terminal 19. The switch 18 may be operated by any other suitable means but herein a thumb-screw 20 threaded into a cap 21 provided on the end of the battery casing serves to force the switch 18 into contact with the terminal 19 to complete the battery circuit. By this means, if the generator should be stopped, or if an accident should occur to the generator circuit of the system the lamp 9 may be lighted so as to enable the user to comply with the law. By providing a lamp of low candle-power for the battery circuit the current consumption is low and the lamp may be operated very economically.

While the lamp 8 may be mounted in any other appropriate manner, it is herein fitted into a socket 22, and the latter extends through a clamping collar 23 formed as a part of the lamp-casing and provided with a suitable clamping screw 24. By this means the lamp socket is rigidly mounted in the lamp-casing in such a manner as to be readily removed and replaced.

While I have herein shown and described one form of my invention for illustrative purposes, and have disclosed and discussed in detail the construction and arrangement incidental to one specific embodiment thereof, it is to be understood that the invention is limited neither to the mere details nor relative arrangement of parts, nor to the

specific embodiment herein shown, but that extensive deviations from the illustrative form or embodiment of the invention may be made without departing from the principles thereof.

Having thus described one embodiment of my invention, what I claim is:

- 10 1. A lighting apparatus for a vehicle comprising, in combination, a lamp-casing having provision for the transmission of light through its rear and its bottom, two lamps of different candle-powers within said lamp-casing and both arranged to shed their rays through the rear and bottom of the casing, 15 separate means for furnishing a lighting supply of the same character to said lamps, and means at will to cut off the supply from one of said lamps.

2. A lighting fixture for vehicles comprising a lamp casing, a battery casing secured to said lamp casing, a low candle-power lamp in said lamp casing and communicating with said battery casing, a switch to connect the same with a battery in said casing, a lamp of comparatively great candle-power disposed laterally of said first lamp in said casing and means for operating said lamp from an electric circuit.

In testimony whereof, I have signed my name to this specification, in the presence of 20 two subscribing witnesses.

ELLSWORTH A. HAWTHORNE.
